KEY-IDENTIFYING DEVICE

Charles F. F'Anson, Kenosha, Wis.

Application May 6, 1936, Serial No. 78,232

2 Claims. (Cl. 40—10)

This invention appertains to door and like keys, and more particularly to novel means for identifying the keys according to the use to which they are to be put.

5 Where a number of keys of substantially the same character are carried on a key-ring, or in a key-case, difficulty is often encountered in selecting the correct key for a particular lock. It is therefore one of the primary objects of my 10 invention to provide a novel device for detachable association with all standard keys for carrying an identification plate or card upon which can be printed or written the door or lock for which the key is to be used, so that the desired 15 and correct key can be instantly picked out from a bunch of other keys.

Another salient object of my invention is to provide a key marker embodying an open frame for receiving the identification plate or card, having means formed thereon for holding the plate or card in position on the frame, and means for detachably securing the same to a key.

Another important object of my invention is to provide a key marker for association with key 25 handles or bows of any configuration embodying a central tongue on the frame for engaging in the key-ring opening of the handle or bow, and bendable tongues for engaging about the sides of the handle adjacent to the key bit or shank.

30 A still further object of my invention is to provide a key identification means of the above character, which will be durable and efficient in use, one that will be simple and easy to manufacture, and one which can be placed upon the market at a small cost.

With these and other objects in view, the invention consists in the novel construction, arrangement, and formation of parts, as will be hereinafter more specifically described, claimed, 40 and illustrated in the accompanying drawing, in which drawing:

Figure 1 is an enlarged front elevation of a standard key showing one of my improved devices connected therewith.

45 Figure 2 is a similar view of the device carrying an identification card showing the key is to be used for the front door.

Figure 3 is an enlarged front elevation of one of the novel devices illustrating the form thereof 50 prior to being associated with a key.

Figure 4 is a longitudinal section through the same taken substantially on the line 4—4 of Figure 3, looking in the direction of the arrows.

Referring to the drawing in detail, wherein 55 similar reference characters designate corre-

sponding parts throughout the several views, the letter K generally indicates a key of the standard type employed for actuating pin tumbler locks. As illustrated, the key K includes the usual handle or bow 5, and the shank or bit 6. The 5 handle 5 is provided with the usual opening 7 for the reception of a key-ring, or the hook of a key-case. The key K forms no part of my present invention, but has merely been shown to illustrate the use of my novel key identification 10 device D.

The novel identification device D is formed from a single stamping of thin metal, or the like, and includes an open frame 10 having formed on its outer periphery a bent-back rim 11. 15 Formed on the opposite sides of the rim 11 are bendable prongs or lips 12, and these prongs are employed for holding an identification card or plate 13 in the frame, as is clearly shown in Figure 4 of the drawing. Obviously, a thin "celluloid" sheet or other transparent protecting plate can be placed over the card 13 to prevent the soiling thereof. The prongs or tongues 12 are bent into intimate contact with the rear face of the plate or guard 13 for holding the same securely 20 against the inner face of the body portion of the frame 10, and this card or plate is adapted to have printed or written thereon the use to which the key is to be put.

Thus, in Figures 1 and 3 the card 13 is shown 30 with the word "Back" thereon, indicating that the key is to be used for the back door of a residence. In Figure 2 the card or plate bears the word "Front," indicating that the key is to be used for the front door. Other cards may bear 35 the words "Office," "Desk Drawer," "Garage," "Ignition," etc.

If preferred and desirable the plates or cards can bear other indicia, such as the name and address of the owner of the key. 40

One of the salient features of the invention is the provision of the novel means formed directly on the flange for permitting the frame to be associated with all shapes of key handles. Thus, the flange 11 at its upper central portion carries 45 an elongated tongue 14, which is adapted to be inserted in the key-ring opening 7 of the key handle or bow 5. After the tongue 14 is inserted in the opening 7, the tongue can be bent back into intimate contact with the rear face of the 50 key. The flange 11 at its lower portion, and on opposite sides of the central tongue 14, has formed thereon bendable side tongues 15 and 16. These tongues are so positioned that the same will lie on opposite sides of the key shank or bit 55

6, and these tongues are adapted to be bent over the key handle into intimate contact with the rear face thereof. The tongues 14, 15, and 16 form a firm securing means for the frame, and 5 prevent twisting and accidental displacement of the frame from the key handle.

In Figure 1 I have illustrated a key with a substantially circular shaped handle, and in Figure 2 10 I have shown the device associated with a key handle of a clover leaf form. In view of the fact that the frame engages only a part of the front face of the key, the same can be associated with key handles of any character.

From the foregoing description it can be seen 15 that I have provided an exceptionally simple and novel form of key identification device, which will permit the quick selection of the correct key for operating a particular lock.

Changes in details may be made without departing from the spirit or scope of my invention, 20 but what I claim as new is:

1. A key-identifying device for association with the handle of a pin tumbler lock key comprising an open frame of a smaller size than the handle 25 of the key including a front plate and a rearwardly directed flange, an identification card fitted in the frame against the front plate and confined by said flange, bendable tongues on the

flange for engaging the rear face of the card, a centrally disposed bendable tongue formed on the upper edge of the frame for engaging in the key-ring opening of a key handle, and oppositely extending bendable tongues formed on the lower side of the frame adjacent to the opposite ends thereof for engaging about the lower edges of a key handle. 5

2. The combination with a standard door key for a pin tumbler lock including a handle having 10 an opening therein for a key-ring, a shank, of a key-identifying device for detachable association with the handle including an open frame of a smaller size than the handle having a front plate and a rearwardly directed marginal flange for 15 engaging against one face of the key handle, an identification card fitted in the frame against the front plate and confined by the marginal flange, bendable prongs on the flange for engaging against the rear face of the card to hold the same 20 in intimate contact with the plate, an upwardly extending bendable tongue formed on the flange for engaging in the opening in the handle, and outwardly extending bendable tongues formed on the lower edge of the flange for engaging about 25 the lower edge of the key handle on opposite sides of the shank.

CHARLES F. I'ANSON.
